UNITED STATES PATENT OFFICE

ROBERT STEWART, OF OZONE PARK, NEW YORK

COMBINATION SPONGE AND WASH RAG

Application filed June 18, 1929. Serial No. 371,863.

The present invention, while capable of a wide range of utility, is peculiarly adapted for embodiment in a washing, scrubbing and rinsing device for use in the bath.

5 An object of the invention is to provide a wash cloth and sponge, so combined that they will not only retain the good qualities of both, but will eliminate undesirable characteristics of the articles which are incidental to their normal independent use.

10 Another object is to provide a neat, attractive dainty article of this character which is of simple, durable construction, entirely sanitary, and well suited to meet the 15 requirements of economical manufacture and convenient manipulation.

In accordance with a preferred embodiment of the invention the sponge is completely encased in a terry cloth cover which 20 protects the skin of the user from direct contact with the sponge proper. The sponge on the other hand tends to maintain the cover fully stretched or distended so that 25 there is no possibility of the terry cloth being left in a moist and crumpled condition after use, such as might be conducive to mildew or might result in the cloth being disagreeable to the touch when required for reuse. The cloth protects the sponge from 30 becoming torn or scraggly and even though disintegration of the sponge finally occurs the broken away pieces thereof are retained in the bag like covering of terry cloth.

35 The invention may be more fully understood from the following description in connection with the accompanying drawings, wherein:

Figure 1 is a perspective view of a combination sponge and wash cloth embodying 40 the invention.

Figure 2 is a longitudinal sectional view therethrough.

45 The sponge 10 is preferably of generally flat oval shape with straight side edges and is held under slight compression within its casing of terry cloth. This casing is made preferably of two similarly shaped but differently colored sections of cloth 11, 12.

50 These sections overlap opposite faces of the sponge and have their edges folded around

the edges of the sponge, turned inwardly and sewed together by a concealed seam or line of stitching 13 which follows the periphery of the oval sponge body about midway between the parallel flat faces thereof.

55 The inwardly folded raw edges of the two fabric sections are thus concealed from view, in order that the device may present a neat and attractive appearance. If desired, the ends of a hanger forming tape loop 14 may also be caught and secured by the line of stitching 13. Preferably each of the fabric sections is of double ply construction although the particular number of laminations may, of course, be varied to suit the 60 requirements of the trade.

65 The terry cloth cover is, in effect, tailored to fit the sponge, to the end that the cloth cover is not apt to slip and slide about on the sponge when in use and the symmetrical varicolored effect is not spoiled by displacement of the fabric relative to the enclosed sponge body.

70 By sewing the fabric sections together with the sponge under slight compression, the sponge holds the cover fully distended and unwrinkled at all times.

75 Obviously the fabric cover might be made of other materials and of many differently colored or otherwise ornate and decorative sections. These sections if once sewed together in a design symmetrical relatively to the flat oval sponge body will retain their 80 symmetry due to the cloth distending and anti-slipping action above discussed.

85 It will thus be seen that there is herein described apparatus in which the several features of this invention are embodied, and which apparatus in its action attains the 90 various objects of the invention and is well suited to meet the requirements of practical use.

95 As many changes could be made in the above construction, and many apparently widely different embodiments of this invention could be made without departing from the scope thereof, it is intended that all matter contained in the above description or 100 shown in the accompanying drawings shall

be interpreted as illustrative and not in a limiting sense.

I claim:

- As a new article of manufacture, a combination sponge and wash cloth including a substantially straight walled slab of spongy rubber, said slab being of substantially uniform thickness, a form determining cover for the spongy slab comprising a pair of similar sections of fabric disposed at opposite sides of the slab and having their edges turned toward each other and connected by a concealed line of stitching following the substantially straight side walls of the slab, the fabric cover being of inelastic rough surfaced material and the sections thereof being so sewed together that the spongy rubber slab is placed under compression whereby the inherent resiliency of the slab maintains the cover stretched taut and prevents slippage of the cover relatively to the slab.

Signed at New York, in the county of New York, State of New York, this 17th

25 day of June, A. D. 1929.

ROBERT STEWART.
